UNITED STATES PATENT OFFICE.

FRED GRUBER, OF NEWARK, NEW JERSEY.

VALVE MECHANISM.

1,342,438.

Specification of Letters Patent. Patented June 8, 1920.

Application filed October 17, 1919. Serial No. 331,426.

To all whom it may concern:

Be it known that I, FRED GRUBER, a citizen of Germany, residing at Newark, county of Essex, and State of New Jersey, have invented certain new and useful Improvements in Valve Mechanism, of which the following is a specification.

This invention relates to internal combustion engines, having particular reference to the valve mechanism for controlling the intake and exhaust of the motive fluid.

The invention has for an object to provide a construction and arrangement of the valve and operating means therefor in which the entire series of valves for an engine of any number of aligned cylinders are mounted as a unit, in the engine, which unit may be easily detached and replaced for purposes of repair or for other purposes.

For further comprehension of the invention, and of the objects and advantages thereof, reference will be had to the following description and accompanying drawings, and to the appended claims in which the various novel features of the invention are more particularly set forth.

Figure 1 of the drawings is a diagrammatic side view of an internal combustion engine showing the application of the invention thereto.

Fig. 2 is an enlarged transverse section on the line 2-2 of Fig. 1.

Fig. 3 is a detail plan view of the valve block.

Fig. 4 is a front view thereof.

Fig. 5 is a side view thereof.

Fig. 6 is a perspective view thereof.

In the drawings 1 indicates the crank case of a four cylinder internal combustion engine and 2 the cylinders thereof. The carburetor is indicated at 3, the intake manifold at 4 and the exhaust manifold at 5, one of the pistons being shown at 6 in Fig.

2. As shown most clearly in this latter figure the cylinders are formed on one side with a laterally projecting ledge 7 which extends across the face of all four cylinders and may be cast integral with the latter as indicated in the drawings or formed separate and bolted in place, the top face of this ledge being flush with the upper end of the body of each cylinder.

This ledge forms a support for the valves which are set therein, the valves being all carried in an elongated block 8 having tapering side and end walls which rests in a

complementary slot cut through the ledge from top to bottom, the height of the block and ledge being equal and the top surface of the block being flush with the top surface of the ledge when the block is in position.

Formed in this block, and suitably spaced the length thereof, are valve chambers 9 and 10 for intake valves 11 and exhaust valves 12 respectively the block being formed with the lateral apertures 13 and 14 which extend inwardly from the side thereof to the valve chamber, which latter are formed by bowing downwardly from the top surface of the block. The outer wall of the ledge 7 is formed with suitable registering openings to receive the branches of the intake and exhaust manifolds, as indicated in Fig. 2. The valves are of the puppet type and seat upon the top surface of the block, and have stems 17 and 18 which extend downwardly through the chambers 9 and 10 and project at their lower ends from the under surface of the block, the valves being yieldingly held in closed position by means of coiled compression springs 20 which surround the projecting stems and bear between collars 21 on the latter and bushings 22 on the under surface of the block. The lower ends of these valve stems project into close proximity to plungers 23 operated in a well known manner by a crank shaft, not shown.

The upper ends of the cylinders are closed by a cap 25 having a downwardly projecting 90 surrounding flange 26. As shown in Fig. 2 this cap is of a width to extend across and cover the ledge 7 so that a passage is provided through the interior of the cap between the valve chambers and the cylinders 95 when the valves are lifted from their seats, suitable partitions dividing the cap to prevent communication through the latter between the cylinders.

To provide for the application of a cooling medium the inner side of the block 8 is formed with a longitudinal recess 28 while a like longitudinal recess 29 is formed in the adjacent wall of the ledge 7.

It will be apparent that by removing the 105 cover the block may be readily lifted from place and with it the entire series of valves.

Having thus described my invention what I claim as new and desire to protect by Letters Patent of the United States is as follows:

1. In an internal combustion engine, a se-

- ries of intake and exhaust valves, an elongated block having tapering side and end walls and lateral apertures in which said valves are mounted, and means for detachably mounting said member on the engine.
5. 2. In an internal combustion engine, a series of cylinders, a ledge extending along said cylinders, an elongated block having tapering side and end walls and lateral apertures removably carried by said ledge, and a series of intake and exhaust valves carried by said block.
10. 3. In an internal combustion engine, a series of cylinders, a ledge extending along said cylinders, an elongated block set in a slot in the said ledge with its top face flush with the top face of said ledge, and a series
15. 15.

of intake and exhaust valves carried by said block.

4. In an internal combustion engine, a series of cylinders, a ledge extending along said cylinders and having its top face flush with the upper ends of the cylinder bodies, an elongated block removably set in a slot in the said ledge with its top face flush with the top face of said ledge, a hollow cap extending across the upper end of the cylinders and the said ledge, and a series of valves carried by said block and opening into the said hollow cap.

20. 25. 30. In testimony whereof I have affixed my signature.

FRED GRUBER.
